UNITED STATES PATENT OFFICE.

CHARLES E. DAVIS, OF CHICAGO, ILLINOIS, ASSIGNOR TO GOODMAN MANUFACTURING COMPANY, OF CHICAGO, ILLINOIS, A CORPORATION OF ILLINOIS.

MINING MACHINE.

Application filed May 23, 1921. Serial No. 471,723.

To all whom it may concern:

Be it known that I, CHARLES E. DAVIS, a citizen of the United States, residing at Chicago, in the county of Cook and State of Illinois, have invented a Mining Machine, of which the following is a specification.

This invention relates to improvements in mining machines, and more particularly to coal cutting machines of the type known as "longwall" machines.

The principal object of the present invention is to provide a machine of the above description which is compact and simple in construction, and suitable for use in narrow places. Other objects will appear from time to time in the following description of a machine embodying the features of my invention.

The invention consists in the combination, construction and arrangement of parts as will hereinafter be described in connection with the accompanying drawings, in which Figure 1 is a top plan view of a mining machine constructed in accordance with my invention.

Figure 2 is a side view of the machine.

Figure 3 is an enlarged plan view of the rear end of the machine with a portion of the top wall broken away to show the mechanism.

Figure 4 is a vertical cross section taken on line 4-4 of Figure 3.

Figure 5 is a vertical cross section taken on line 5-5 of Figure 3.

Figure 6 is a vertical cross section taken on line 6-6 of Figure 3.

Figure 7 is a transverse vertical cross section taken on line 7-7, Figure 3.

Figure 8 is a rear view of the machine.

Figure 9 is a horizontal cross-section taken on line 9-9 of Figure 2.

Figure 10 is a vertical cross-section taken on line 10-10 of Figure 3.

Figure 11 is a vertical cross-section taken on the line 11-11 of Figure 3.

Longwall mining machines generally have as a common feature of construction an elongated frame provided with a cutting element adapted to extend from one side thereof.

The machine is dragged along the mine floor longitudinally of the mine wall, with the cutting element extending from one side of the machine to form a kerf. A motor is mounted on the frame, and has operative

connection with the cutting element, and also with suitable draft mechanism for feeding or moving the machine to the coal.

In the present invention I have provided a novel arrangement of the feeding mechanism and cutter chain gearing by combining them at one end of the motor housing thereby reducing the dimensions of the machine to a minimum. The cutter bar is pivotally mounted at one end of the machine so as to cut at either side thereof, and a winding drum of the draft mechanism is mounted to rotate concentrically about the axis of the cutter arm. The cutter chain and the winding drum are driven independently of each other, each being driven through suitable gear reducing mechanism, but clutch means is provided whereby the winding drum may be connected with the cutter arm, to swing it about its vertical axis, either for feeding the cutter bar to the coal, or for positioning it with respect to the machine.

I also provide a novel means of tilting the cutter bar so as to extend laterally from the machine at various angles with respect to the face upon which the machine rests.

Referring now to the drawings, the mining machine comprises three main portions, namely, a motor casing A; a head frame B; and the cutter bar C. I have shown an electric motor with its armature 10 arranged longitudinally of the motor casing A, but it will be understood that any equivalent motor may be substituted if desired. The motor casing A has a bottom face 11, which forms a base upon which the entire machine is moved. The head frame B is mounted rearwardly of the motor casing, and is preferably in the form of a housing 12, enclosing the operating mechanism and provided with a removable cover 13. The rearward end of said housing has an overhanging portion 14, forming an undercut recess opening at the rear and sides of the machine, and the cutter bar C is pivotally mounted in this recess so that it may be swung at an angle of approximately 180°, that is to say, from one side of the machine to the other, so as to cut on either side thereof.

The cutter arm C may be provided with an endless cutter chain of any approved pattern (not shown).

Reference to Figure 4 shows the preferred construction for mounting the cutter arm on

the head frame B. The inner end of cutter arm is provided with an offset portion 15 having a hub 16 journaled in an upwardly extending stud 17 formed integral with the 5 head frame B. A retaining ring 18 has threaded engagement above the upper end of the hub 16 to retain the latter in place on said stud.

Means for driving the cutter chain is 10 closed in the housing 12, and includes a pinion 22 mounted on the motor armature 23 and meshed with gear 24 carried on a horizontally disposed shaft 25. A beveled pinion 26 rotates with the gear 24, and is 15 meshed with a second beveled pinion 27 mounted on the vertically disposed stud 28. Said stud is preferably retained in place by means of a pin 29 splined thereto and secured at its upper end by a suitable bearing 20 stud 30, mounted in the cover 13, and secured at its lower end to the frame as shown. A clutch member 32 is mounted on the exterior of the hub 33 of beveled pinion 27, said clutch member being movable vertically on 25 said hub to engage a gear member 34, carried on stud 30. Means for operating clutch member 32 may comprise any suitable construction, such as a clutch fork 37 (see Figure 7), pivoted to the frame. A forked arm 38 carried on a shaft 39 engages one side of the clutch fork 37. The shaft 39 extends through the side wall of housing 12, and is operated by handle 40. A self-aligning thrust bearing 35 is preferably inserted in 35 an annular recess 36 formed in the upper end of hub 33, to take up the thrust of the bevel pinion 27.

The gear member 34 is meshed with a horizontally disposed gear 21, carried on shaft 40 20, which extends through the hub 16 of the cutter arm, and is connected with cutter chain sprocket 19, mounted under the offset portion 15 of the cutter bar.

The feeding mechanism, comprising a 45 winding drum and gearing affording various driving speeds thereto, is also contained in the housing 12. The winding drum 45 is rotatably mounted on the exterior of the stud 17, which has already been described 50 as being formed integral with the head frame B, and within which the cutter arm C is journaled. A flexible cable 46 or its equivalent, is wound on the drum, and when in operation, the cable is adapted to be anchored at a distance from the machine so 55 that the machine may be moved at various speeds depending upon the speed of rotation of the winding drum 45. The cable 46 may be lead to either side of the machine as desired and suitable guiding sheaves 47, 47, are positioned on opposite sides of the frame adjacent said drum, so that the cable may be trained rearwardly along either side and over suitable guiding sheaves 48, 48, at the 60 opposite end of the machine, in any desired 65

manner necessary for controlling the movement of the machine. Sheaves 47, 47, preferably are movable vertically on spindles 47^a, 47^a, so as to allow the cable to "spool" on the drum 45.

The winding drum 45 is provided with a lower flange 49, having a plurality of notches 50, 50, formed therein. In the drawings, four of these notches are shown.

Said drum rests on a forwardly extending 70 support 51, preferably formed integral with the casing 12, said support being provided with a plurality of notches 52, 52, preferably three in number, one of which is arranged in the center of the rear edge of said support, and the others being arranged at angles of approximately 90° therefrom, on opposite sides of the hub 17. A vertically movable latch member 53 is pivoted on the cutter arm C adjacent the drum flange 49 75 and the support 51, said latch being movable into position in notches 50 of the former, or 52 of the latter. Normally said latch member will be retained by gravity in one of the notches 52, of the support, so as to lock the 80 cutter arm in one of the cutting positions at right angles to the frame, or in position longitudinally with respect to the frame, in which latter position the cutter arm is usually placed while the machine is being moved 85 from place to place. Suitable means may be provided for moving the latch, such as an inclined slot 54, adapted to receive a suitable handle for raising the latch when desired. By means of arrangement just described, the 90 cutter arm will be normally maintained in one of the positions indicated, but when it is desired to change the position of the cutter arm the drum is rotated until one of the notches 50 registers with the latch 53. Said 95 latch may then be raised into engagement with the drum flange and the drum is rotated in the direction desired to move the cutter arm therewith to a new position. A plurality of recesses 55 suitable to receive a removable handle, bar, or the like, may also be provided in the periphery of the drum flange 49, so as to allow the drum to be rotated 100 by hand when desired.

As has already been stated, the mechanism for operating the winding drum 45 is located in the housing 12. This mechanism includes gear member 61 meshed with an armature pinion 60, and carried on a counter shaft 62. Said gear member 61 forms a portion of a planetary transmission device 63, shown in detail in Figure 5, in which it will be seen that gear member 61 is mounted adjacent casing 64, and forms therewith an enclosed housing. Said casing is free to 115 rotate with respect to its bearings, excepting that its rotation may be controlled by means of a suitable friction band 65. The gear member 61 is provided with a sun gear pinion 66, which meshes with a planetary 120

gear member 67, carried in a suitable cage 68, keyed to the countershaft 62. Said planetary gear member 67 is integral with a second gear member 69. The latter gear has a larger pitch diameter than the first named gear member, and is meshed with an internal gear 70, carried on the inside of the casing 64. A plurality of planetary gear members 67 and 69 may be provided if desired. The tension of the friction band 65 may be controlled in any suitable manner such as rocking arm 71 (see Figure 7) attached to one end of the band, and connected by a link 71^a to a bell crank lever 71^b extending through the side wall of casing 12, and connected to a link 42 extending to the rear end of the machine. Said link 42 is controlled by any suitable means such as a hand-wheel 43, having screw threaded engagement at one end of an arm 44 pivoted on the frame and connected at its opposite end with the link 42.

By means of the planetary gear device just described, a speed reduction is afforded, and a variation in speeds may be produced by varying the tension applied by the brake band 65 which controls the rotation of the casing 64. This planetary device allows the clutch devices and reverse gears to be hereinafter described, to be easily engaged and disengaged while the mechanism is in operation.

Means for reversing the direction of rotation of the winding drum comprises a sliding gear 72, splined on a suitable sleeve 73, mounted on a countershaft 74. Said sliding gear is adapted to have selective engagement with a gear pinion 75, splined on the countershaft 62 to drive in one direction, or with an idler gear 76 on stub shaft 76' made integral with gear pinion 75 so as to drive said sliding gear in the reverse direction. A neutral position for said sliding gear is also provided intermediate the pinion 75 and the idler 76. Said sliding gear may be shifted by any suitable means such as a yoke 77, projecting from an endwise movable shaft 78, and controlled by a lever 79 extending to the rear of the machine.

The countershaft 74 is journalled in suitable bearings 80, 80 and carries a worm gear 81, which meshes with a worm wheel 82, associated with a pinion 83 rotatably mounted on a vertically-disposed shaft 84.

A hub portion 85 of the pinion 83, extends downwardly through worm wheel 82. Means are provided for operatively engaging the worm wheel and pinion 83, which means comprise a vertically movable clutch member 86, mounted on the shaft 84 below said members, and having clutch teeth 87, adapted to engage clutch teeth 88 and 89 on said worm and pinion, respectively. The arrangement is such that the clutch teeth 87

are always in engagement with one of the rotatable gear members, as for instance, as is shown in the drawing, in which said clutch teeth are continually engaged with gear member 83, so as to rotate therewith, but may be moved upwardly to engage the clutch 88 associated with the worm gear 82, to form a driving connection therewith. Any suitable means for controlling the clutch 86 may be provided, such as a shifter yoke 91 mounted on a shaft 92 extending through the side of the housing 12, and connected with an arm 93, which in turn is operated with the lever 94, extending to the rear of the machine as shown.

The gear member 83 is meshed with a large vertically disposed gear member 90, arranged below the sprocket chain gear 21, and connected directly to the upper flange of the cable drum 45, by any suitable means.

Another feature of my invention relates to the tilting of the cutter bar so that it will extend laterally from the machine at various angles with respect to the base upon which the machine rests. To this end I have provided means whereby the entire head frame B and the mechanism associated therewith, may be rotated with respect to the motor casing A, using armature shaft 23 as the axis of rotation. It will be understood that the motor and motor housing constitutes a large proportion of the weight of the entire machine. The motor casing is provided at its forward end with an annular bearing member 95, concentric with the armature shaft 23, and fitting into the rear wall of the housing 12. A retaining ring 97 is attached to the outer end of bearing member 95 by any suitable means, such as a threaded connection 97^a, and secures the motor casing and head frame together and affording rotation of these elements with respect to each other. The bottom wall of the housing 12 is inclined upwardly toward the side margins thereof, so as to give the housing at least a partial contact with the ground in all positions of the latter, as indicated at 98. The relative position of the two elements is controlled by a vertically disposed screw 99, mounted on one of said elements, as for instance the head frame housing 12 (see Figure 10), at one side of the machine, and carrying a threaded nut 100 engaging the motor casing A. Said screw may be operated by any suitable means such as a socket wrench adapted to engage the upper end 101 thereof.

The use and operation of the machine above described is as follows:

The normal cutting operation of a long-wall machine consists in moving the machine along the mine face with the cutter arm substantially at right angles with the longitudinal axis of the machine. The machine is moved by means of the draft cable,

anchored in advance of the machine, and connected with the feeding device on the machine.

In longwall mining machines, as heretofore constructed, the cutter bar is usually moved about its pivot by attaching one end of the draft rope to the cutter arm, and then actuating the feeding mechanism so as to swing the cutter arm about its axis into the desired position with respect to the machine. The draft rope is then disconnected from the cutter arm and anchored in advance of the machine so the cutting may proceed in the usual manner. In a machine constructed in accordance with the present invention, the cutter arm is pivotally moved by direct engagement with the feed drum 45 independent of the draft rope. In other words, in order to swing the latter toward, or away from, the face, sufficient slack is provided in the draft rope, and the lock 53 on the cutter arm is brought into engagement with a notch 50 on the winding drum flange 45, in which operative position the cutter arm may be pivotally retracted from the kerf, and then returned to cutting position in the coal. This feature is particularly advantageous when it is desired to move the cutter arm out of the kerf, as for instance, while the cut is being made, to replace cutter bits, or to tilt the cutter bar.

The means described for tilting the cutter bar with respect to the body portion of the chain is useful where the bottom of the mine is rolling or uneven, or where impurities are encountered which may be avoided by changing the angle of the cutter bar in the manner described. The arrangement is such that the cutter bar is tilted longitudinally of its axis, so that the outer end moves vertically, when the cutter bar is held in the position at right angles to the machine frame shown in dotted lines in Figure 1. This is the normal cutting position of the cutter arm. It will be noted however, that when the cutter bar is in longitudinal position with respect to the main frame, that is to say, with its longitudinal axis parallel with the axis about which the head frame B has limited pivotal movement, (as shown in full lines in Figure 1), the resulting movement of the cutter arm when the head frame is pivoted about its axis, will be to tilt the cutter bar transversely, so that the cutting edge of the bar may be directed upwardly or downwardly. Under some conditions it is desirous to perform the cutting operation with the cutter arm in this longitudinal position, in which case the machine is operated after the manner of a shortwall machine, and by tilting the cutter bar transversely, the cutter bar may be made to follow rolling bottom. It is therefore obvious that this feature may also be applied in the construction of shortwall machines,

in which the cutter bar is always positioned longitudinally of the main frame during the cutting operation.

Among other features of construction described is the arrangement of the feeding mechanism on the head frame B, and driven from the same end of the armature shaft as the gearing associated with the cutter chain. By means of the construction described, it will be seen that the point of connection of the draft rope to the machine is located directly at the inner end of the cutter arm. This arrangement has distinct advantages over other machines of this class in which the feeding mechanism is located at a distance from the cutter arm. The standard practice has heretofore been to locate the feeding mechanism at the end of the motor casing opposite the cutter arm. In all such constructions, where the draft rope is connected at a point remote from the cutter bar, it is obvious that the intervening parts of the machine must necessarily be of heavy and rigid construction in order to withstand the pulling stress incident to the cutting operation. In my present invention, however, it will be seen that little stress from the draft rope is placed on the machine frame excepting where it is connected directly at the inner end of the cutter bar, and therefore it is possible to construct the other portions of the machine frame, such as the motor casing, of relatively light material.

One of the novel features of the gearing mechanism described above is a provision or means for reversing the direction of movement of the winding drum independent of the direction of movement of the cutter chain. In the embodiment illustrated this means comprises the sliding gear 72 having selective engagement with pinion 75 and reversed idler pinion 76. This arrangement allows the winding drum to be reversed, so as to afford slack in the draft rope when desired, or to wind the draft rope in the opposite direction when it is desired to reverse the cutter arm and cut from the opposite side of the machine. Furthermore, by means of this reversing mechanism, the winding drum may be connected with the cutter arm so as to move the cutter arm pivotally in either direction independent of the direction of movement of the cutter chain about the cutter arm.

It will also be noted, that the mechanism affording a driving connection between the motor and the feeding drum 45 includes the following elements in the order named: first, a planetary gear and clutch device (63); second, a reverse gear mechanism (72, 75 and 76); third, a worm and gear (81 and 82); fourth, a clutch (86); and fifth, a pinion and gear (83 and 90). The worm and gear are preferably of the non-

reversible, self-locking, type, so that during the cutting operation, if the friction clutch on the planetary gear mechanism 63 is released, or the sliding gear 72 is shifted to neutral or reverse, the tension on the draft rope 46 will be maintained without slackening the same, by reason of the self-locking worm interposed between the cable drum and both the planetary gear and the reverse gear. The rope may be slackened when desired by throwing out the clutch 86, between the worm and the drum.

I claim as my invention:

1. In a mining machine, a motor, a casting for said motor, a support connected at one end of said motor casing, a cutting element pivotally mounted on said support, a rotatable feeding element also mounted on said support, having operative connection with said motor and flexible draft means operatively connected with said rotatable feeding element.

2. In a mining machine, a motor, a casting for said motor, a support connected at one end of said motor casing, a cutting element pivotally mounted on said support, a rotatable feeding element also mounted on said support having operative connection with said motor, and means affording operative connection between said cutting element and said feeding element to move the former about its axis.

3. In a mining machine, a motor, a casting for said motor, a support connected at one end of said motor casing, a cutting element pivotally mounted on said support, a rotatable feeding element also mounted on said support having operative connection with said motor, means affording an operative connection between said cutting element and said feeding element to move the former about its axis, and means for locking said cutting element in predetermined positions with respect to said support.

4. In a mining machine, a motor, a casting for said motor, a support connected at one end of said motor casing, a cutting element pivotally mounted on said support, a rotatable feeding element mounted concentrically with the axis of said cutting element, and flexible draft means operatively connected with said feeding element.

5. In a mining machine, a frame, a motor, a cutting element pivotally mounted on said frame to swing in a horizontal plane, a rotatable draft feeding element mounted concentrically with the pivotal axis of said cutting element and having operative connection with said motor, and means affording an operative connection between said cutting element and said feeding element.

6. In a mining machine, a frame, a motor, a cutter bar pivotally mounted on said frame to swing in a horizontal plane, and provided with a cutter chain, a rotatable

draft feeding element mounted concentrically with the pivotal axis of said cutter bar and having operative connection with said motor, means affording an operative connection between said cutter bar and said feeding element to rotate the former about its axis, and means for operating said cutter chain independent of said feeding element.

7. In a mining machine a frame, a motor, a cutting element pivotally mounted on said frame to swing in a horizontal plane, a rotatable draft feeding element mounted concentrically with the pivotal axis of said cutting element and having operative connection with said motor, means normally locking said cutting element with respect to the frame, and means affording driving connection at will between said cutting element and said feeding element.

8. In a mining machine, an elongated frame comprising a motor casing and a support mounted at one end thereof, a motor in said casing, a cutter bar pivotally mounted adjacent the outer end of said support and provided with a cutter chain, gear reduction mechanism affording operative connection between said cutter chain and said motor, a winding drum mounted on said support, and gear reduction mechanism affording operative connection between said motor and said winding drum to drive the latter at a lower speed than said cutter chain.

9. In a mining machine, an elongated frame comprising a motor casing and a support mounted at one end thereof, a motor in said casing, a cutter bar pivotally mounted adjacent the outer end of said support and provided with a cutter chain, gear reduction mechanism affording operative connection between said cutter chain and said motor, a winding drum mounted on said support, gear reduction mechanism affording operative connection between said motor and said winding drum to drive the latter at a lower speed than said cutter chain, and means affording operative connection between said low-speed gear mechanism and said cutter bar, to move the latter about its axis.

10. In a mining machine, a frame having a vertically disposed stud, a cutter arm journalled in said stud, and a winding drum rotatably mounted about said stud.

11. In a mining machine, a motor, a frame having a vertically disposed stud, a winding drum rotatably mounted about said stud, a cutter arm having a journalled bearing in said stud and provided with a cutter chain, a shaft mounted axially of said journalled bearing, provided with a sprocket for said chain, and a gear carried by said shaft having operative connection with said motor.

12. In a mining machine, a support, a

- motor, a cutting element pivotally mounted on said support and provided with a cutter chain mechanism affording a driving connection between said motor and said cutter chain, a rotatable feeding element, means operable independently of said cutter chain driving mechanism including a reversing mechanism affording an operative connection between said feeding element and said motor, and means affording operative connection between said cutting element and said feeding element to swing the former about its axis. 13. In a mining machine, a support, a motor, a cutting element pivotally mounted on said support and provided with a cutter chain mechanism affording a driving connection between said motor and said cutter chain, a rotatable feeding element, means operable independently of said cutter chain driving mechanism including a reversing mechanism and a self locking worm and gear, affording an operative connection between said feeding element and said motor, and means affording operative connection between said cutting element and said feeding element to swing the former about its axis. 14. In a mining machine, a support, a motor, a cutting element pivotally mounted on said support and provided with a cutter chain mechanism affording a driving connection between said motor and said cutter chain, a rotatable feeding element, means operable independently of said cutter chain driving mechanism, including a clutch device and a self-locking worm and gear, affording an operative connection between said feeding element and said motor, and means affording operative connection between said cutting element and said feeding element to swing the former about its axis. 15. In a mining machine, a support, a motor, a cutting element pivotally mounted on said support and provided with a cutter chain mechanism affording a driving connection between said motor and said cutter chain, a rotatable feeding element, means operable independently of said cutter chain driving mechanism, including two clutch devices and an intermediate self-locking worm and gear affording an operative connection between said feeding element and said motor, and means affording operative connection between said cutting element and said feeding element to swing the former about its axis. 16. In a mining machine, a motor, a cutter bar provided with a cutter chain, driving mechanism operatively connecting said motor and said cutter chain, a rotatable feeding element having flexible draft means connected therewith, and mechanism operable independently of said chain driving mechanism and affording operative connection between said motor and said feeding element including a reversing mechanism, and a self-locking worm and gear interposed between said feeding element and said reversing mechanism. 17. In a mining machine, a frame, a motor, a cutter arm pivotally mounted on said frame and provided with a cutter chain, means affording operative connection between said motor and said cutter chain to drive the latter, and means including a reversing mechanism independent of said last named means affording operative connection between said motor and said cutter arm to swing the latter about its pivotal axis. Signed at Chicago, Illinois, this nineteenth day of May 1921.

CHARLES E. DAVIS.
